[57] CLAIM

The ornamental design for an electronic information key, as shown and described.

DESCRIPTION

FIG. 1 is a perspective view of an electronic information key embodying my new design;

FIG. 2 is a side elevational view of the design of FIG. 1;

FIG. 3 is a bottom plan view (a top plan view if included would be the same) of the design of FIG. 1;
FIG. 4 is an end elevational view taken from the left-hand end of FIG. 2, and
FIG. 5 is an end elevational view taken from the right-hand end of FIG. 2.
